UNITED STATES PATENT OFFICE.

DANIEL B. KENNEY, OF HUNTINGTON, WEST VIRGINIA.

HOSE-RETRIEVING DEVICE.

Application filed March 24, 1922. Serial No. 546,529.

To all whom it may concern:

Be it known that I, DANIEL B. KENNEY, a citizen of the United States, residing at Huntington, in the county of Cabell and 5 State of West Virginia, have invented certain new and useful Improvements in Hose-Retrieving Devices, of which the following is a specification.

The present invention relates to a device 10 for use in dispensing air or any other similar fluid medium, and has for its primary object to provide a device of this character which embodies novel features of construction, whereby the dispensing pipe is automatically held in an out of the way position when not in use, although it is conveniently 15 accessible at all times and can be readily drawn into operative position when it is desired to dispense the compressed air.

At the present time it is customary for all 20 gasoline supply stations and other public stations of a similar character to provide "free air" for the use of their patrons in inflating tires. The compressed air is ordinarily 25 distributed through a flexible tube or pipe which is dragged from place to place as it is needed, and which is usually dropped by each patron when he has finished inflating his tires, without any thought of 30 coiling it up or putting it back in any particular place. The flexible tube used in this manner is frequently stretched across a pavement or street, so that it is a menace to 35 pedestrians who are liable to be tripped thereby, and in being pulled or dragged over the ground it becomes covered with grease and dirt, so that it is disagreeable to handle and may even carry dangerous disease germs. Furthermore, a tube which is han- 40 dled in this manner becomes rapidly worn from being dragged over the ground, and has a comparatively short life.

The foregoing objections are overcome by the present invention which provides 45 means for automatically retracting the flexible dispensing tube and holding it in an out of the way position as soon as it is released. However, the flexible dispensing tube is always in such a position that it 50 can be conveniently grasped and used for any purpose such as inflating a tire within a certain radius around the dispensing stand.

With the above and other objects in view the invention consists in certain combina- 55 tions, arrangements and associations of the parts as will more fully appear as the de-

scription proceeds, the novel features thereof being pointed out in the appended claims.

For a full understanding of the invention reference is to be had to the following 60 description and accompanying drawings in which:

Figure 1 is a side elevation of a compressed air dispensing stand, which is constructed in accordance with the invention, 65 the dispensing tube being illustrated by full lines in inoperative position and by dotted lines in operative position.

Figure 2 is an enlarged vertical sectional view through the head which has a swiveled 70 connection with the upper end of the stand.

Figure 3 is a transverse vertical sectional view taken on the line 3—3 of Figure 2.

Figure 4 is a horizontal sectional view 75 taken on the line 4—4 of Figure 2 looking upwardly.

Figure 5 is a detail view of the pivotally mounted coupling member.

Corresponding and like parts are referred 80 to in the following description and indicated on all of the views of the drawings by like reference characters.

Referring to the drawings, which illustrate one of many possible embodiments of 85 the invention, the numeral 1 designates a pedestal which is mounted in some convenient relation to a tank or other source of compressed air supply. The pedestal is illustrated as being provided at its upper 90 end with a casing 2 which is provided with a lower dial 3 and an upper pressure gauge 4. These members are associated with a special form of valve, such as that disclosed fully in my co-pending application for a 95 fluid pressure control device and automatic cut off, Serial No. 538,112, filed Feb. 20, 1922. This construction, as is fully set forth in the said co-pending application enables a tire to be accurately inflated to any prede- 100 termined degree of pressure without danger of either over or under inflation. The pointer 5 which is mounted to play over the dial 3 is rotated manually until the end thereof points to the graduation of the dial 105 which corresponds to the degree of pressure with which it is desired to inflate the tire. The pressure gauge 4 acts as a check upon the pressure control device and is in communica- 110 tion with the pipe leading to the tire so that it registers the building up of the pressure within the tire until the final degree of pres-

sure is reached, at which time the automatic valve mechanism which is controlled by the positioning of the pointer 5 acts to cut off the air supply. This construction is fully set forth and claimed in my copending application and no claims based thereon are made in this application.

A tubular standard 6 extends upwardly from the top of the casing 2 and a head 7 is swiveled thereon, said head being hollow and being provided at its base with a depending neck 8 which fits around the upper end of the head. Pins or screws 9 which are carried by the depending neck 8 are adapted to have the ends thereof brought into engagement with a groove 10 at the top of the casing 6. The head 7 is thereby securely fastened to the standard, although it is free to rotate thereon. It may also be noted that the base of the head 7 is provided with a shoulder 11 which rests upon the top of the standard, and assists in supporting the head thereon.

One side of the head or housing 7 is extended laterally and provided with a lateral opening 12. Extending through this lateral opening is a substantially Z shaped fitting 13, said fitting being provided at an intermediate point in its length with a transversely disposed hub portion 14 by means of which it is pivotally mounted within the head in such a manner as to swing freely about a horizontal axis. In the present instance the ends of the hub portion 14 are shown as recessed to receive the extremities of pins 15 which are fitted in the sides of the head 7 and extend through the walls thereof on opposite sides of the opening 12.

The inner end of the fitting 13 is shown as provided with a nipple 16 by means of which it is secured to the upper end of a length of flexible tubing 17 which extends downwardly through the interior of the tubular standard 6 and is suitably connected to a pipe leading from the source of compressed air supply. This inner end of the fitting 13 is also provided with a wing or extension 18 which is connected to the upper end of a tension spring 19, said spring extending downwardly through the tubular standard 1, and being secured to some fixed support, such as the inwardly projecting lug 20. The outer end of the fitting 13 is connected to a pipe 21 which normally extends upwardly, having a hooked end 22 which is connected to the flexible dispensing tube 23. The length of the flexible tube 23 is just slightly less than the combined lengths of the pedestal 1, standard 6, and pipe 21. When the pipe 21 is in an upright position, as indicated by full lines on Figure 1, the flexible tube 23 will hang in a substantially vertical position at one side of the pedestal.

The free end of the flexible dispensing tube 23 is provided with a conventional tire

valve engaging member 24, and when it is desired to inflate a tire or other article, the operator grasps the flexible tube 23 and fitting 24 and forcibly pulls the same into a position where the fitting 24 can be applied to the tire valve casing. This will result in swinging the pipe 21 outwardly and downwardly, as indicated by dotted lines on Figure 1, the said pipe swinging about the hub portion 14 of the Z shaped fitting 13 as an axis. This results in placing the spring 19 under tension, so that as soon as the dispensing tube 23 is released the pipe 21 will again swing into an upright position, thereby retracting and lifting the flexible tube 23 into an out of the way position. The flexible tube 23 may be drawn out for use within a reasonable distance from the pedestal 1, and the swivel connection between the head 7 and the standard 6 enables it to rotate about a vertical axis so that the dispensing tube 23 can be used at any point within a certain radius around the base of the standard. However, as soon as the dispensing tube is released it is instantly retracted and lifted into an elevated position so that it is not permitted to be dragged over the ground and left in dangerous positions when not in use. In fact, the flexible tube is normally lifted above the ground at all times so that it is prevented from becoming covered with grease and dirt and is also protected against the wear which is always occasioned by the dragging of these tubes over the ground or pavement.

While one particular embodiment of the invention has been illustrated and described in detail for the purpose of making the idea of the invention clear, it will be understood that many modifications and changes can be made in the details of construction without departing from the spirit of the invention.

Having thus described my invention what I claim as new and desire to secure by Letters Patent is,

1. A hose retrieving device including a tubular standard, a head rotatably mounted thereon, a tubular arm pivotally mounted upon the head, a laterally projecting fitting at the pivot end of the arm, a spring engaging the fitting and normally tending to swing the arm into an upright position, a flexible supply pipe extending through the tubular standard, and connected to the fitting, said fitting being formed to establish communication between the supply pipe and arm and a dispensing hose connected to the swinging end of the tubular arm and arranged to be retrieved thereby.

2. A hose retrieving device including a tubular standard, a head rotatably mounted thereon, a tubular arm pivotally mounted upon the head, a laterally projecting fitting at the pivot end of the tubular arm, and having opposing trunnions journaled in the

head to permit movement of the arm in a vertical plane, said fitting extending over the tubular standard and through one side of the head, a spring extending through the tubular standard and connected to the fitting for normally tending to swing the tubular arm into an upright position, a flexible supply pipe extending through the standard and connected to the fitting, and a dispensing hose connected to the swinging end of the arm and arranged to be retrieved thereby when not in use.

3. A hose retrieving device including a **Z** shaped fitting pivotally mounted upon the support and having an air passage therethrough, a tubular arm connected to one end of the fitting, a flexible supply pipe connected to the other end of the fitting for delivering air through the fitting to the arm, yielding means normally tending to swing the arm into a predetermined position, and a dispensing hose connected to the swinging end of the tubular arm and arranged to be retrieved by the swinging arm when not in use.

4. A hose retrieving device including a support, a **Z** fitting pivotally mounted thereon having an air passage therethrough, a tubular arm connected to one end of the **Z** fitting, a flexible supply pipe connected to the other arm of the **Z** fitting to pass air through the fitting to the arm, a spring en-

gaging the **Z** fitting and normally tending to swing the same to bring the tubular arm into a predetermined position and a dispensing hose connected to the swinging end of the tubular arm and arranged to be retrieved thereby when not in use.

5. A hose retrieving device including a tubular standard having an annular groove at the top thereof, a hollow head rotatably mounted thereon, means on said head engaging in the groove to prevent accidental displacement while allowing for rotative movement, a **Z** fitting pivotally mounted upon the head with one arm thereof projecting over the tubular standard, said fitting having an air passage therethrough, a flexible supply pipe extending through the tubular standard and connected to the said arm, a spring also extending through the tubular standard and connected to the said arm, a tubular arm connected to the other arm of the **Z** fitting to receive the air from the supply pipe through the fitting, and normally held yieldably in an upright position by the action of the spring, and a dispensing hose connected to the swinging end of the tubular arm and arranged to be retrieved by the arm when not in use.

In testimony whereof I affix my signature.

DANIEL B. KENNEY.
